IRONING MACHINE

John W. Racklyeft, Cleveland, Ohio, assignor to
 The Apex Electrical Manufacturing Company,
 Cleveland, Ohio, a corporation of Ohio

Application November 19, 1936, Serial No. 111,695

20 Claims. (CL 38—59)

This invention relates to ironing machines and it constitutes a continuation-in-part of my co-pending application Serial No. 735,040, which was filed on July 13, 1934 and issued as Patent No. 2,087,447, July 20, 1937, for Ironing machine mechanism.

The present invention has for its objects the provision of an improved form of ironer roll drive, in which the driving gears of the roll drive are adapted to be yieldingly shifted into and out of meshing engagement with each other, special means being provided to insure the quiet and positive engagement of the roll driving gears; the provision of a simple and compact ironer roll driving mechanism; including driving gears located internally of the ironer roll; the provision of a power-operated ironing machine having a minimum number of clutches; and the provision of an ironer roll drive as described, in combination with an ironer of the type in which either the roll or the shoe is the shiftable member and in which the ironer roll drive is automatically connected to drive the roll when the roll and shoe are shifted to an operative pressing position and automatically disconnected when the roll and shoe are separated one from the other.

These and other objects of the invention will become more apparent and better understood after consideration has been given to the following detailed description of the invention taken in connection with the drawings which show, merely by way of illustration, structure adapted for carrying out the objects of the invention.

Stated in general terms, the invention relates to an ironing machine employing a padded roll and a heated shoe and power means for effecting both the rotation of the roll and the shifting of the roll into and out of pressing contact with the heated ironer shoe. Easily operable means in the form of coil spring clutches, are provided for controlling the shifting of the roll into and out of pressing contact with the heated shoe and for permitting the machine to be used for pressing operations at which times the rotation of the roll is prevented.

Mechanism in the form of an internal gear carried inside the roll and a driving pinion adapted for meshing engagement therewith, are provided for automatically effecting the rotation of the roll when it is moved into pressing contact with the heated shoe, the roll drive being automatically disconnected through disengagement of the gears when the roll is moved out of

contact with the shoe. The driving pinion of the ironer roll is yieldingly or resiliently mounted inside the roll so that the meshing engagement of the internal gear and this pinion may be effected in a quiet and positive manner when the roll is moved into contact with the shoe.

In the drawings, Figure 1 is a side elevational view of an ironing machine showing one form of the invention; Figure 2 is an enlarged sectional view, taken on line 2—2, Figure 1; Figure 3 is an enlarged end view of the roll and shoe taken on line 3—3, Figure 1, with certain of the parts broken away to illustrate the mechanism inside the roll at one end thereof; Figure 4 is an enlarged sectional view taken on line 4—4, Figure 1, showing the roll driving gears in their operative or roll-driving position; Figure 5 is an enlarged detail view of the roll-driving gears when in their inoperative or separated position; Figure 6 is a detail sectional view taken on line 6—6, Figure 5; Figure 7 is a side elevational view of an ironing machine, illustrating a modification of the invention; Figures 8 and 9 are enlarged detail sectional views taken on lines 8—8 and 9—9 of Figure 7, the roll supporting member 41 being omitted from Fig. 9 for clarity; Figure 10 is a detail view corresponding in section to Figure 8 and illustrating a modified form of mounting for the roll driving pinion; Figure 11 is a sectional view taken on line 11—11, Figure 10; Figure 12 is a view corresponding in section to Figures 8 and 10, illustrating yet another modification of the mounting for the roll driving pinion; Figure 13 is a sectional view taken on line 13—13, Figure 12; Figure 14 is a side elevational view of an ironing machine, illustrating a further modification of the invention; Figure 15 is a sectional view taken on line 15—15, Figure 16; Figure 16 is an enlarged detail sectional view taken on line 16—16, Figure 15; Figure 17 is a side elevational view, of an ironing machine illustrating a further modification of the invention; Figure 18 is an enlarged end elevational view of the machine shown in Figure 17, with portions of the machine broken away and shown in section; Figure 19 is a sectional view taken on line 19—19, Figure 18; Figure 20 is a detail view of the roll drive showing the roll-driving gears in disengaged position; and Figure 21 is an enlarged sectional view taken on line 21—21, Figure 18.

The ironing machine shown in Figure 1, which illustrates one form of the invention, comprises a supporting structure in the form of a base member 1 and supporting legs 2 attached to the base member. A hollow gear case 3 is carried on top

of the base member at one end thereof. The gear case constitutes a standard for supporting an ironer roll 4 solely from one end thereof. The roll 4 is provided with suitable padding 4a. A bracket 5 is located intermediate the ends of the base member and it provides a support for an arm 6. An ironer shoe 7 is secured to and supported from the upper end of the arm 6. The shoe 7 is heated by means of a heating element 7a, which may be in the form of an electrical resistor and at the rear of the shoe a cover 7b is provided for the heating element.

The shoe supporting arm 6 is mounted upon a shaft (not shown) housed within a tube 8 which rests at one end on the bracket 5 and at its other end the tube is received in a hollow boss 10 which forms a part of the gear case 3. Suitable means, such as shown in my earlier referred to application, may be provided for manually shifting the shoe toward and away from the roll and for effecting yielding pressing contact between the roll and the shoe when these ironing elements are in pressing contact with each other.

An electric motor 11 mounted inside the gear case 3 is provided for driving the ironer. The armature shaft of the motor 11 is provided with a pulley 12 for driving a belt 13 which connects the motor to the pulley 14 of the ironer mechanism. The pulley 14 is fixed to a shaft 15 and secured thereon by means of a stud 14a. The shaft 15 is provided with a worm 15a which meshes with and drives a worm gear 16. The worm gear 16 is mounted upon a hub 16a which extends to either side of the worm gear. The hub 16a is journaled on a bearing sleeve 20a carried by the gear case boss 20b. The axially extending portions of the hub are surrounded, one by a part of the clutch spring 17 and the other by a part of the clutch spring 18.

The clutch spring 17 is fastened at one end to a shaft 20 coaxial with the hub 16a and it is journaled inside the bearing sleeve 20a. One end of the clutch spring 18 is fastened to an eccentric member 21 which is also journaled on the sleeve 20a. The eccentric 21 is received in one end of a connecting link or rod 22, which in turn is pivotally connected at its other end to a crank arm 23 fixed to a rocker shaft 24. A pinion 25, as is shown in Figures 4, 5 and 6, is fixed to the end of the shaft 20 remote from the clutch spring 17.

A manually operated clutch control member 26 is provided for controlling the clutch spring 17. This member has an associated stop arm 27 adapted to be moved into and out of the path of the end 28 of the spring 17 to effect the disengagement and engagement of the clutch spring 17 with respect to the hub 16a of the worm gear for the purpose of disconnecting and connecting the worm gear with respect to the shaft 20 and its pinion 25.

A second manually operable clutch control member 30 is provided for controlling the operation of the clutch which is formed in part by the spring 18. The control member 30 has a pair of associated stop arms 31 and 32 which are adapted to be moved into and out of the path of the end 33 of the spring 18 and in this manner effect the disconnection and connection of the clutch which is formed by the spring 18 and a part of the worm gear hub 16a. The clutch just described controls the operation of the eccentric 21 and its connecting link 22 and in this manner controls the oscillation of the shaft 24 and its crank arm 23 to which the link 22 is connected.

The clutch which is formed by the spring 18 is normally in a disengaged position, and when the control member 30 is manipulated, the clutch spring 18 is released for effecting the engagement 5 of the clutch which is maintained through one-half revolution of the eccentric 21, whereupon the end 33 of the clutch spring 18 is engaged by one or the other of the arms 31 or 32 and in this manner a one-half revolution clutch is provided 10 for the purpose of rotating the eccentric 21 in steps of one hundred and eighty degrees. The shaft 24 is thus oscillated to one or the other of its limiting positions, for the purpose of moving the ironer elements into and out of pressing contact with each other as will be described further 15 presently.

The gear housing 3 is provided with a hollow boss 35, and a tubular member 36 is carried by the boss for the purpose of supporting the roll 20 solely from one end thereof. The outer end of the tube 36 is provided with a bracket 37 for rotatably receiving and supporting the remote end of the oscillatable shaft 24. A crank arm 38 is secured to the end of the shaft 24 and this arm is provided with a bearing 40 for rotatably supporting the end of the roll remote from the gear case.

The other end of the roll is rotatably mounted upon a bearing member 41 carried by an eccentrically located bracket 42 fixed to the oscillatable shaft 24 at a point adjacent to the gear case 3. In view of the foregoing, it is apparent that when the shaft 24 is oscillated, the bearings 40 and 41 will be oscillated with it, and in this 25 manner the roll may be shifted into and out of pressing contact with the ironer shoe, as is illustrated in Figures 3 and 4.

An internal ring gear 43 is located inside the roll at the end thereof next to the gear case 40. This gear is fixed to the roll and it is adapted 30 for meshing engagement with a driving pinion gear 44. The pinion gear 44 is rotatably mounted upon a stub shaft 45 carried by a U-shaped bracket 46 which in turn is rotatably carried by the shaft 20 to which the gear 25 is fixed. A stop 45a which contacts with the bearing 41 is provided to prevent the pinion gear 44 from digging into the internal gear 43 and to limit the teeth of the gear and pinion to pitch line engagement 45 when these gears are moved into mesh with each other.

By means of the aforesaid structure, the gears 25 and 44 are maintained at all times in mesh with each other. A coil spring 47, having one 55 end in contact with the tube 36 and its other end in contact with the stub shaft 45, provides a means for urging the pinion gear 44 toward the internal gear 43 and to the position illustrated in Figure 5 when the roll and shoe are 60 out of engagement with each other.

The U-shaped member 46 has a projecting part 49 which engages with the boss 35 to provide a stop for the shifting movement of the gear 44 in one direction. The yielding support of the pinion 44 which is provided by the U-shaped bracket 46 and the spring 47 serves to facilitate 65 and insure quiet meshing engagement between the internal gear 43 and the pinion 44. The axis of the bodily movement or shifting of the pinion 44 is arranged so that the line of reaction 70 between the pinion 44 and the gear 43 will be in a direction to maintain these gears in proper mesh with each other and to obviate the possibility of the gears jumping out of mesh when 75 under load.

The reaction of the gears 43 and 44 has a slight tendency to shift the top of the U-shaped member to the right, as viewed in Figure 5 by reason of the location of the pivotal support of the bracket 46 to one side of the reaction line of the gears and in this manner proper meshing engagement of the pinion 44 and the gear 43 are maintained at all times when the gears are in mesh with each other. The stop 48 is arranged to maintain the gears 43 and 44 out of mesh when the roll 4 is moved out of contact with the shoe.

In the form of the invention illustrated in Figures 7 to 9, there is provided a base 1, supporting legs 2, a gear case 3, ironer roll 4, a bracket 5, a support arm 6, a shoe 7 and a tube 8 similar to those previously described in connection with Figure 1.

Mechanism under control of the manually operable members 26 and 30 is housed within the gear case 3. The mechanism and the control means provided therefor are substantially the same as the corresponding structure previously described. The roll 4 is supported from a tube 36 by means of elements 37, 38, 40 and 41, similar to the elements of like number which were previously described.

In the latter form of the invention, the roll drive is slightly different in that the internal gear 43 is located nearer to the midpoint of the roll and it is driven through the action of a single pinion gear instead of a pair of gears, as in the case of the device shown in Figure 1. At its outer end, the driving shaft 20 is provided with a universal joint indicated generally by the numeral 50 for the purpose of connecting the shaft 20 to a shaft 51. At its other end, the shaft 51 is connected by means of a universal joint 52 to a short-shaft 53 which is rotatably journaled in a bracket 54 pivotally mounted on the oscillatable shaft 24.

A pinion 55 is fixed to rotate with the shaft 53. The bracket 54 is apertured at 56 for the accommodation of the roll supporting tube 36 and one of the ends of the aperture 56 provides a stop for limiting the movement of the bracket member about the axis of the shaft 24 in one direction. A spring 57 is provided for urging the bracket 54 and the pinion 55 which it carries in a direction toward the internal gear 43 of the roll.

In view of the foregoing, it is apparent that when the roll is shifted into contact with the shoe, the internal gear 43 will move into meshing engagement with the pinion 55 and in this manner the roll is rotated. In the event that the teeth of the gears 43 and 55 do not line up and intermesh at the time of initial contact, the spring 57 will permit the gear 55 to shift with the gear 43 until meshing of the teeth of these gears is effected.

The pinion supporting bracket 54 is mounted for movement on an axis a slight distance to one side of the line of the reaction forces between the gears 43 and 55, so that the stated reaction will tend to hold the gears 43 and 55 in mesh with each other. When the roll 4 is moved away from the shoe, the apertured portion 56 of the bracket 54 will contact with the tube 36 and thus hold the pinion 55 out of mesh with the gear 43.

In the form of the invention illustrated in Figures 10 and 11, a slightly different form of mounting is provided for the roll driving pinion 55. This pinion is connected to the driving shaft 51 through the interconnection of a universal

joint 52 and a short shaft 53, similar to those described in connection with the modification shown in Figures 7 to 9.

The short shaft 53 is journaled in a bearing member 61 formed in the outer end of a pin 62 which is slidably mounted in a suitable aperture extending cross-wise of the tube 36. A stud 63 which secures a washer 64 on the pin 62 may be provided to limit the movement of the pin in one direction. The pin 62 may be provided with a downwardly extending arm 65 having a bifurcated end 66 for receiving the oscillatable shaft 24 to provide a supplemental guide and support means for the pin.

A spring 67 is provided for moving the mounting of the pinion 55 in a direction radially outwardly of the axis of the roll, so that when the roll is moved into contact with the shoe, the internal gear 43 is moved into meshing engagement with the pinion 55 in a manner similar to that previously indicated in connection with the earlier described forms of the invention. When the roll is moved away from the shoe, the washer 64 engages with the roll supporting tube to hold the pinion 55 out of mesh with the internal gear 43.

In the form of the invention illustrated in Figures 12 and 13, the pinion 55 and its shaft 53 are rotatably carried by a bracket 70 which is freely journaled on the oscillatable shaft 24. The position of the shaft 24 is slightly shifted to the right, as viewed in Figure 12, from the position it occupies in the previously described forms of the invention, thus requiring a slight modification of the gear case 3 and the link 22. The weight of the gear 55 and the elements associated therewith is sufficient to cause the gear and its bracket to move in a direction toward the internal gear 43 of the roll, and the present construction does not require the use of a spring for this purpose, although a spring may be used if desired.

When the roll is moved toward the shoe, the internal gear 43 moves into meshing engagement with the driving pinion 55 and when the roll is moved away from the shoe, the internal gear 43 moves out of mesh with the pinion 55. The bracket 70 is provided with a stop arm 71 for contact with the tube 36 for the purpose of holding the pinion 55 out of engagement with the internal gear 43 when the roll occupies its retracted position with respect to the ironer shoe.

In the form of the invention illustrated in Figures 14 to 16, there is provided a base 1 having legs 2, a gear case 3, a roll 4, a bracket 5, a shoe-supporting arm 6, a shoe 7 and a tube 8, similar to those first described, and similar operating mechanism under control of the manually operated members 26 and 30 is located within the gear case 3.

The present construction differs from the constructions earlier described in that the roll 4 is supported from a point intermediate its ends by means of a pair of bearing members 72 and 73 which are rotatably carried on a shaft 74. The shaft 74 is fixed to the upper end of a crank arm 75 which is in turn fixed to an oscillatable shaft 24a similar to the shaft 24 previously described but somewhat shorter in length.

The roll-supporting tube 36a is also somewhat shorter in length than the tubes 36 previously described and it is carried from a boss 35a which is located below the axis of the roll instead of on the axis as is the case of the boss 35 for the earlier forms of the invention.

The oscillatable shaft 24a is located inside the

tube 36a and the outer end of this tube provides a bearing for supporting the outer end of the shaft 24a. In this form of construction, the roll driving pinion 55 is carried by a U-shaped bracket 76 which is rotatably journaled upon the tube 36a. The bracket 76 is slotted at 77 for receiving a pin 78 which is fixed to the tube 36a. The slot and the pin are provided for the purpose of limiting the movement of the U-shaped bracket 76.

In view of what has been said in connection with the earlier forms of the invention, it is apparent that when the roll 4 is moved into contact with the shoe, the internal gear 43 will move into meshing engagement with the pinion 55 which is connected to the shaft 20 by means of the couplings 50 and 52 and the shaft 51. In the event that the teeth of the gear and pinion do not line up properly, the pinion is free to move with the gear until the gear teeth do line up, whereupon the force of reaction between the gears insures the maintaining of proper meshing engagement between the pinion 55 and the internal gear 43 in the manner described in connection with the form of the invention illustrated in Figures 12 and 13.

When the roll is shifted away from the shoe, the stop which is provided by the pin 78 and the slot 77 of the U-shaped bracket 76 serves to hold the pinion 55 out of meshing engagement with the internal gear 43, as in the case of the form of the invention illustrated in Figures 12 and 13. A spring similar to the one shown in Figures 5 and 6 might be employed to urge the pinion 55 toward the internal gear 43 if desired.

The changing of the position of the shaft roll supporting tube 36a from the position of the corresponding tube 36, previously described, will necessitate a slight modification of the gear case 3 and a relocation of the tube supporting boss, as will be understood by anyone skilled in the art to which this invention relates.

In the various forms of the invention just described wherein the reaction of the gears tends to maintain them in mesh with each other, it is preferred to mount the driving pinion for bodily movement about an axis slightly to one side of the line of reaction between the roll driving pinion and the internal gear of the roll so that these gears will be maintained in mesh without, however, causing undue pressure on the teeth of the gears by reason of the manner in which they are mounted.

In most of the forms of the invention shown herein, the force of gravity may be relied upon to provide for the yielding intermeshing engagement between the internal gear of the roll and its driving pinion and, if desired, a spring may be used with any of the different modifications to further assure that the contemplated bodily movement of the ironer roll driving pinion will take place.

In all of the ironers disclosed herein, the ironer roll rotates in a clockwise direction, as viewed from the end of the roll adjacent to the gear case, so that the articles to be ironed may be placed up on top of the roll and thus fed directly to the ironer shoe.

Due to the use of the two roll driving pinions 25 and 44, in the form of the invention illustrated in Figures 1 to 6, it is necessary to rotate the worm gear 16 in a direction opposite to the direction of rotation of the roll in order to rotate the roll in the desired direction.

The form of the invention illustrated in Fig-

ure 17 comprises a base 1, supporting legs 2, a gear case 3a, an ironer roll 4, a bracket 5, a shoe supporting arm 6, an ironer shoe 7, a tube 8, all of which are much the same as the corresponding elements previously described.

The present modification differs from the forms of the invention earlier described in that the shoe is the shiftable member rather than the roll. The shoe-shifting mechanism which is housed 10 inside the gear case 3a is slightly different from the mechanisms previously described and in order to accommodate the gearing of the present machine, it is necessary to use a gear case of slightly larger size than the gear cases previously 15 described.

The gear case 3a is provided at one side with a hollow boss 10 for receiving one end of a tube 8 at the other end of which the shoe-supporting arm 6 is carried. The operating mechanism 20 of the machine is driven by a motor 11 having a pulley 12 for driving a belt 13 which is connected to the driven mechanism pulley 14. The pulley 14 is fixedly connected to a shaft 15 which carries a worm 15a in mesh with a worm gear 16. 25 The worm gear 16 is provided with axially extending hub or sleeve portions 16a which co-operate with coiled clutch springs 17 and 18 similar to those previously described.

The clutch spring 17 is fixed at one end to a 30 shaft 20 which is journaled in a bearing sleeve 20a carried by the gear case boss 20b. One end of the clutch spring 18 is fixed with respect to an eccentric 21 which is also journaled on the sleeve 20a. The eccentric 21 is received in one 35 end of a connecting rod 22a and at its other end the rod 22a is connected by means of a pin 80 to a crank arm 81. The other end of this crank arm is fixedly attached to one end of a torsion rod 82 and the opposite end of the torsion rod 40 is fixedly connected to the shoe-supporting arm 6 which is pivotally connected at 83 to the rear part of the shoe 7.

In view of the foregoing, it is apparent that 45 when the eccentric 21 is rotated, it will serve to shift the shoe toward and away from the roll. The control of the movement of the eccentric is the same as for the ironer mechanisms previously described and it is operated to rotate in steps of 180 degrees, so that for one movement of the eccentric, the shoe is moved into pressing contact with the roll and for the other movement of the eccentric, the shoe is shifted away from the roll.

The roll is carried by a pair of bearing members 72a and 73a, journaled for movement on a 50 roll supporting tube 36b which is rigid with the gear case 3a. An internal gear 43 is secured to the roll alongside of the bearing member 73a. The shaft 20 projects outwardly from the gear case 3a and into the roll where it is provided with a pinion 25 similar to the gear of like number previously described.

The shaft 20 provides a mounting for a bracket 55 which is rotatably journaled on this shaft. 55 The bracket is provided with a bearing pin 85 which forms a bearing for a second pinion 86 which meshes at all times with the pinion 25. The pinion 86 is adapted for meshing engagement with the internal gear 43. A spring 87 is provided to urge the bracket 84 and the pinion 86 in a direction toward the adjacent portion of the internal gear 83. Beneath the shaft 70 60 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 is mechanically shifted into and out of meshing engagement with the internal gear 43.

The mechanism for accomplishing the shifting of the pinion 86 comprises a connecting link 90 which is pivotally connected at one end to the pin 80 and at its other end it is pivotally connected at 91 to a crank member 92 which is fixed to one end of a tubular shaft 93. The other end of the tubular shaft 93 is provided with a cam 94 which is adapted to be moved into and out of meshing engagement with the extension 88 of the pinion bracket. The tubular shaft 93 is journaled in a suitable bearing member 95 which may be formed integrally with the gear case 3a.

In view of the foregoing, it is apparent that when the shoe-shifting mechanism is operated to move the shoe into contact with the roll, the connecting rod 90 will be moved downwardly to the position shown in Figure 18, lifting the cam 94 out of contact with the extension 88 of the pinion bracket, thus permitting the pinion 86 to move under influence of the spring 87 into mesh with the internal roll gear 43.

The reaction between the pinion 86 and the roll gear 43 tends to maintain these gears in meshing engagement with each other. When the shoe is shifted away from the roll, the lever 90 moves upwardly and rotates the cam 94 into engagement with the bracket extension 88, and in this manner, the pinion 86 is shifted out of meshing engagement with the internal gear 43 of the roll. Additional mechanism to permit the machine to be used for pressing operations is provided for preventing at times the rotation of the roll when the shoe is moved into pressing contact therewith.

This mechanism comprises a manually operable control 96 located outside the gear case 3a and fixed to a shaft 97 which is pivotally mounted inside the gear case. The shaft 97 is provided with a bracket 98 which is pivotally connected at 99 to a link 100 which in turn is pivotally connected at 101 to a crank 102 which is fixed with respect to one end of a shaft 103. The shaft 103 is journaled inside the tubular shaft 93 and at its opposite end it is provided with a cam 104 located alongside the cam 94.

The cam 104 is pinned at 105 to the shaft 103 and when the manual control 96 is moved downwardly, a corresponding movement of the cam 104 takes place and the cam is thus shifted into engagement with the extension 88 of the pinion supporting bracket, and in this manner, the pinion 86 may be prevented from meshing with the internal gear 43 under influence of the spring 87. When the manual control member 96 is moved to the position shown in Figure 18, the cam 104 is moved away from the extension 88 of the pinion bracket and the shifting of the pinion is controlled entirely by the cam 94 and the elements which are associated with this cam and with the shoe-shifting mechanism. The control 96 and the parts associated with it are fitted so that there is sufficient friction to maintain the control 96 in its adjusted positions.

In the forms of the invention illustrated in Figures 7 to 16, where but one roll driving pinion is employed, it is necessary in order to drive the roll in the specified direction, to have the worm gear 16 rotate in the same direction that the roll is driven.

In addition to reversing the direction of rotation of the motor and the gearing in the gear case 3 in adapting the mechanism shown in

connection with the first form of the invention to the modifications of the invention illustrated in Figures 7 to 16, it is also necessary to reverse the winding of the clutch springs 17 and 18 so that they will wrap around the portions of the worm gear sleeve 16a which they overlie, when the sleeve rotates in a clockwise direction, as viewed from the gear case end of the machine. This result could be accomplished by interchanging the clutch springs 17 and 18. In the previously referred to application, of which the present application forms a continuation-in-part, the gearing inside the gear case is arranged to rotate in a clockwise direction, as viewed from the gear case end of the machine, and as is necessary when the roll is driven by the type of gearing shown in Figures 7 to 16.

In all of the constructions described herein, it is intended that the internal gear in the roll and its driving pinion mesh with each other at least partially, before the roll and shoe contact each other so that no substantial load is imposed on the gears at the instant of their engagement or disengagement. Because of this, the roll driving connection is effected in a quiet manner and the specified arrangement has the further advantage of reducing wear on the ends of the gear teeth and thus preventing such portions of the gear teeth from quickly becoming worn or broken.

The foregoing description and the accompanying drawings to which it relates, describes what might be termed the preferred modes of practicing the invention. It is to be clearly understood, however, that the invention includes each and every novel feature or combination of novel features herein disclosed, subject only to the restrictions of the prior art, and that the invention may assume other forms and it is not to be limited to the particular and specific structure shown and described herein.

Having thus described my invention what I claim is:

1. An ironing machine comprising, cooperating ironing members mounted for relative shifting movement into and out of pressing contact one with the other, one of said members being a rotatably mounted roll, means for effecting the relative shifting movement of said ironing members, and power means for rotating said roll including a source of power and a disconnectible driving connection between said source of power and said roll in the form of a driving and a driven gear located inside the roll and movable into and out of meshing engagement with each other, said driving gear mounted on a pivoted gear carrier, the pivotal axis of the gear carrier being located with respect to the axis of rotation of the driving gear so that the coaction of the gears when in mesh tends to move the driving gear toward the driven gear.

2. An ironing machine comprising, cooperating ironing members mounted for relative shifting movement into and out of pressing contact one with the other, one of said members being a rotatably mounted roll, means for effecting the relative shifting movement of said ironing members, and power means for rotating said roll including a source of power and a disconnectible driving connection between said source of power and said roll in the form of a driving and a driven gear located inside the roll and movable into and out of meshing engagement with each other, one of said gears being rotatably mounted upon a support, said support being movably

mounted on a member below the axis of rotation of said last named gear.

3. An ironing machine comprising, cooperating ironing members mounted for relative shifting movement into and out of pressing contact one with the other, one of said members being a rotatably mounted roll, means for rotatably supporting said roll from a point substantially midway between its ends, means for effecting the relative shifting movement of said ironing members, and power means for rotating said roll including a source of power and a disconnectible driving connection between said source of power and said roll in the form of a driving and a driven gear inside the roll near the midpoint thereof and movable into and out of meshing engagement with each other, one of said gears being rotatably mounted upon a yielding support to facilitate the meshing of the gears when they are moved into engagement with each other.

4. An ironing machine as defined in claim 3, in which the driven gear is fixed to and movable with the roll.

5. An ironer roll drive comprising a driving pinion inside the roll mounted for movement radially of the roll axis, an internal gear carried by the roll adapted for meshing engagement therewith, means for urging the pinion in a direction toward the internal gear, and power means for rotating the pinion and for shifting the roll and thereby shifting the internal gear into and out of meshing engagement with said pinion.

6. An ironing machine comprising, cooperating ironing members mounted for relative shifting movement into and out of pressing contact one with the other, one of said members being a rotatably mounted roll, means for effecting the relative shifting movement of said ironing members, and power means for rotating said roll including a source of power and a disconnectible driving connection between said source of power and said roll in the form of a driving and a driven gear located inside the roll, one of which is movable into and out of meshing engagement with the other, the other of said gears being rotatably mounted upon a yielding support to facilitate the meshing of the gears when they are moved into engagement with each other.

7. An ironing machine comprising, cooperating ironing members mounted for relative shifting movement into and out of pressing contact one with the other, one of said members being a rotatably mounted roll, means for effecting the relative shifting movement of said ironing members, and power means for rotating said roll including a source of power and a disconnectible driving connection between said source of power and said roll in the form of a driving and a driven gear, said driven gear being secured inside said roll and movable therewith into and out of meshing engagement with said driving gear, said driving gear being rotatably mounted upon a yielding support to facilitate the meshing of the gears when they are moved into engagement with each other.

8. An ironing machine comprising, cooperating ironing members mounted for relative shifting movement into and out of pressing contact one with the other, one of said members being a rotatably mounted roll, means for effecting the relative shifting movement of said ironing members, and power means for rotating said roll including a source of power and a disconnectible driving connection between said source of power and said roll in the form of a driving and a driven

gear located inside the roll, said driven gear being fixed to said roll and movable therewith into and out of meshing engagement with said driving gear, said driving gear being rotatably mounted upon a yielding support to facilitate the meshing of the gears when they are moved into engagement with each other.

9. An ironer roll drive of the type described, comprising a driving member, a driving pinion inside the roll, an internal gear carried by the roll and movable into and out of mesh with said pinion, means for laterally shifting said roll toward said pinion, shaft and flexible coupling means for connecting said pinion to the driving member and means for mounting said pinion for bodily oscillatable movement about an axis below the axis of pinion rotation so that the force of drive will tend to move the pinion towards the internal gear.

10. An ironer roll drive of the type described comprising a driving shaft, a driving pinion inside of the roll, an internal gear carried by the roll and movable into and out of mesh with said pinion, power means for laterally shifting said roll, shaft and flexible coupling means for connecting said pinion to the driving shaft, means for mounting said pinion for bodily shiftable movement and means to limit said bodily shiftable movement of the pinion toward the gear during their engagement.

11. An ironer roll drive of the type described comprising a driving shaft, a driving pinion inside of the roll, an internal gear carried by the roll and movable into and out of mesh with said pinion, power means for laterally shifting said roll, shaft and flexible coupling means for connecting said pinion to the driving shaft, means for mounting said pinion for bodily shiftable movement and means to limit said bodily shiftable movement of the pinion toward the gear during their engagement, said last-named means comprising a member adjacent said pinion and a member adjacent said gear, said members adapted to contact each other when said pinion and gear are brought into engagement, said members being proportioned to limit the teeth of the gear and pinion to a pitch line engagement.

12. In an ironing machine, a shoe, a roll, means for shifting the roll against and away from the shoe, an internal gear carried by the roll and movable therewith, a power shaft, a second shaft connected thereto by a flexible coupling, a pinion on said second shaft, said second shaft being biased to a position in which the pinion is in mesh with the internal gear when the roll is against the shoe.

13. An ironing machine comprising a supporting stand, a gear casing at one end of said stand, a roll support projecting laterally from said gear casing and a roll mounted on said support, an ironing shoe arranged to cooperate with said roll, said roll and its mounting comprising a cylindrical metal tube, a pair of spaced transverse plates arranged in the mid portion of said tube, a shaft mounted in said roll support having one end projecting into said gear casing and the other end thereof provided with an eccentric operatively associated with said plates, and power means connected to said one end of said shaft whereby rotation of the shaft and its eccentric effects a bodily movement of the roll with respect to said shoe.

14. An ironing machine comprising a supporting stand, a gear casing at one end of said stand, a roll support projecting laterally from said gear

casing and a roll mounted on said support, an ironing shoe arranged to cooperate with said roll, said roll and its mounting comprising a cylindrical metal tube, a pair of spaced transverse plates arranged in the mid portion of said tube, a shaft mounted in said roll support having one end projecting into said gear casing and the other end thereof provided with an eccentric operatively associated with said plates, and power means connected to said one end of said shaft whereby rotation of the shaft and its eccentric effects a bodily movement of the roll with respect to said shoe, and means to rotate said roll comprising a driven gear and a driving pinion arranged inside said roll between said gear casing and said transverse plates.

15. In an ironing machine, a shoe, a roll, means for shifting the roll against and away from the shoe, an internal gear carried by the roll and movable therewith, a power shaft, a second shaft connected to said power shaft by a flexible coupling, a pinion on said second shaft, said second shaft being biased to a position in which the pinion is in mesh with the internal gear when the roll is against the shoe, and means including a slotted guideway arranged to mount said second shaft and the pinion for independent bodily movement.

16. In an ironing machine, a shoe, a roll support, a roll, means for shifting the roll against and away from the shoe, an internal gear carried by the roll and movable therewith, a power shaft, a second shaft connected to said power shaft by a flexible coupling, a pinion on said second shaft, said second shaft being biased to a position in which the pinion is in mesh with the internal gear when the roll is carried against the shoe, a member provided with a slot carried by said roll support to mount said second shaft and pinion thereon for independent bodily movement, said member including a stop to limit the position of said pinion with respect to said gear.

17. In an ironing machine, a pair of ironing members one of which comprises a roll, one of said members being movable into and out of pressing engagement with the other, a driving connection for the roll comprising a driving gear and a driven gear, the driven gear being carried by the roll and being movable into and out of engagement with the driving gear by move-

ment of the roll transverse to its axis, power means for shifting said movable ironing member into and out of pressing engagement with the other ironing member and for moving the roll transverse to its axis toward and away from said driving gear, and means for supporting one of said gears for yielding bodily movement under the tooth reaction forces present when the teeth are misaligned and independent of the position of said shifting means and away from the other gear upon operation of the shifting means to move the roll toward the driving gear.

18. In an ironing machine, a shoe, a hollow roll, a frame having driving means for rotating the roll, a tube projecting from said frame, said roll surrounding said tube, bearing means rotatably supporting the roll, said bearing means being eccentrically pivoted on the tube, and means extending through the tube for pivoting said bearing means on the tube whereby the roll is moved relative to the shoe.

19. In an ironing machine, a shoe, a roll, a tube projecting within the roll, a shaft journaled in the tube, a roll supporting bearing within the roll eccentric of the shaft and supported by the tube, and a connection between the shaft and bearing whereby the bearing rotates with and about the axis of the shaft to move the roll relative to the shoe.

20. In an ironer, a shoe, a hollow roll, a drive shaft extending axially within the roll, a driving gear within the roll on the shaft, an internal gear within and carried by the roll, said internal gear surrounding the driving gear and being movable into and out of mesh with the driving gear by bodily movement of the roll transverse to its axis and toward and away from the driving gear, means within the roll for supporting the roll for rotation and for said movement toward and away from the driving gear, shifting means for effecting engagement and separation of the roll and shoe and for moving the roll toward and away from the driving gear, and means providing a yielding support for one of said gears permitting yielding movement thereof away from the other gear and independent of the position of the shifting means under the tooth reaction forces whereby jamming of the gear teeth is prevented as the teeth are moved into mesh.

JOHN W. RACKLEYFT.
